UNITED STATES PATENT OFFICE.

HAROLD F. RICHARDS, OF CINCINNATI, OHIO.

PROCESS FOR ARTIFICIALLY CURING AND CAKING THE INSIDE OF PIPES.

Application filed April 5, 1922. Serial No. 548,886.

To all whom it may concern:

Be it known that I, HAROLD F. RICHARDS, a citizen of the United States, residing at the city of Cincinnati, in the county of Hamilton and State of Ohio, have invented certain new and useful Improvements in Processes for Artificially Curing and Caking the Inside of Pipes, of which the following is a specification.

10 My invention relates to the process, method and device for artificially breaking in, curing, and caking smoking pipes without rendering them foul and unfit for sale as a new article of manufacture.

15 It is a well known fact that new tobacco pipes, especially wooden pipes, must be "broken in" by the smoker, that is, the smoker must continually smoke the pipe until the inside of the bowl of the tobacco

20 pipe is coated with a layer of carbon and binding materials resulting from the combustion of tobacco; during this process of caking the inside of the bowl of the pipe, the smoker is obliged to suffer the unpleasant

25 "bites" and odors which result from the contact of burning tobacco with the raw wood, before the pipe has been "broken in."

The object of my invention is to obviate all these objections and inconveniences and

30 artificially smoke the pipe, and place upon the bowl, on the inside thereof, a layer or layers of carbon and thus the pipe can be sold new as an article of manufacture, and at the same time be "broken in" at the time

35 of purchase, ready to be used as if the pipe had been "broken in" by the purchaser.

Essentially, the method consists in coating the inner surface of the pipe-bowl with suitable materials and then treating these

40 materials with heat, or with heat and a forced draft of air, until the materials have been changed into a hard cake which clings firmly to the bowl and possesses the essential properties of the cake or crust that ordinarily accumulates on the bowl when the pipe

45 is smoked for pleasure. This cake is a component part of the pipe wall and not a separate lining; and when the pipe is smoked for pleasure the cake is not consumed, but serves

50 as a basic wall upon which further accumulation of cake takes place naturally.

The materials which are spread on the inner surface of the bowl may include sugar, which, when sufficiently heated will yield a

55 deposit of carbon; finely divided tobacco, or derivatives of tobacco, to serve as a binder

for the granular carbon which results from the charring of the sugar; licorice to bind the carbon and also to impart a palatable quality to the resulting cake; or any combination or mixture of these and any other materials which are capable of being formed into a firm cake that will perform the functions of the natural cake in preventing contact of burning tobacco with the wood of the pipe when it is smoked for pleasure and thus suppressing and eliminating the unpleasant and sickening tastes and odors which result when a new and uncaked pipe is smoked. Other flavoring ingredients may be added to the mixture, if desired, so that the resulting cake will impart a pleasant fragrance to the smoke when the pipe is put in use.

In the accompanying drawing forming a part of this specification:

Fig. 1, is a side view of a pipe, the bowl part being in section to illustrate construction,

Fig. 2, is a plan view of a pipe, looking down upon the same, the bowl part turned up,

Fig. 3, is a section of the bowl of a pipe and part of the stem thereof,

Fig. 4, is a section of a pipe bowl showing one coating of the carbon on the inside thereof,

Fig. 5, is a similar view, showing a second coating of carbon on the interior of the pipe bowl,

Fig. 6, is a similar view to that shown in Figs. 4 and 5, except that still another coating has been added and the caked carbon has been smoothed and evened up, on the inner surface of the carbon coating, and

Fig. 7, is a view of a pipe in side elevation, the bowl part being in section, showing my device for artificially smoking the pipe, in position, and showing the same in elevation and partly in section.

In the drawings, the bowl of the pipe is marked 1, the stem thereof 2, the mouth-piece 3, and the draft tube 4.

In the bowl 1, at the bottom thereof, on the inside, I place a plug 5 of asbestos, mineral wool, mica, transite or other non-heat conducting or poorly conducting or not readily combustible material, or any other suitable material, see particularly Fig. 7.

In Fig. 7, I show an air tube 6, through which I produce a continuous or intermittent suction or air draft, by means of any

device or apparatus, to which the tube leads, which is not shown in the drawings, as such means are well known in the art. This tube 6, in the present instance, reaches down to 5 plug 5, and at its lower periphery is provided with a multiplicity of small slits, holes or interstices as 7. Around this tube 6 I wind electric wire 8, in coil formation, and 10 9 and 10 are the electric wires, the terminals of which lead to some current-producing source, not shown, as being well known in the art.

In Figs. 1, 4, 5, and 6, the character 12 represents a line of demarcation, between the 15 carbon layer 13 and the plain wooden part face 14 at the bottom of the bowl 1, to which no carbon layer has been applied, although a carbon layer may be placed over the whole inside periphery of the pipe as shown in Fig. 20 3, marked 15.

In order to cake a pipe, the air-intake at the bottom of the bowl is first stopped up with asbestos or other protecting material; the mixture described above is then spread 25 over the inner surface of the bowl, and finally a tube wound with a coil of wire is inserted upright in the middle of bowl. Suction apparatus, provided with suitable 30 devices for regulating the air-craft and rendering it intermittent if desired, is attached to the upper end of this tube, which projects well above the pipe; and the lower end of the tube is provided with openings or notches so that a current of air passes 35 down through the annular space between the bowl and the tube, and up through the tube. Heat is applied to the coating on the bowl by passing an electric current through the heating coil, and a forced draft of air may 40 be applied during any portion of the period of heating, by means of the suction apparatus. By repeating this process as many times as desired, a cake of any required thickness may be formed in the bowl. The 45 cake may be given a smooth or regular surface either by polishing or by so regulating the composition and texture of the applied materials that a regular surface results directly from the final heating.

If it is desired further to improve the 50 smoking properties of the pipe, tobacco or other suitable materials may be packed in the annular space between bowl and tube and this material ignited and smoked artificially with the apparatus already described above.

During the heating and charring of the 60 materials which are spread on the inner surface of the bowl, or during the process of producing combustion within the bowl, no smoke passes through the stem of the pipe; and the wood around the air-intake at the bottom of the bowl may be left clean and new-looking, if the obstacle which closes 65 the air-intake be suitably designed and dis-

posed. Thus a sharp line of demarcation may be produced between the caked and uncaked portions of the bowl, and the finished pipe will be obviously new and fit for sale. In order further to improve the appearance 70 of the caked pipe, the bowl may be originally bored so as to have a narrow shoulder of wood projecting near the bottom of the pipe, and the cake may then be fitted evenly and smoothly against this shoulder of wood. 75 Thus the cake can be made flush and even with the uncaked wood, and the pipe presents a new and freshly manufactured appearance which shows a prospective purchaser that it has not been smoked in the 80 natural way.

It will be noticed in the drawing, see particularly Figs. 4 and 5, that when one of the caked coatings is applied it has a somewhat roughened or an uneven surface, so 85 that the next coating applied will adhere to the coat upon which it is applied more perfectly and also adhere more readily.

By carbon is meant any carbonaceous matter or composition of matter containing carbon and by-products. After a smoker has "broken-in" his new pipe, it is caked on the inside of the bowl with an adhering matter formed by the combined charring of the wood and the burning of the tobacco, thus a 90 combined element or caked coating results; the pipe at this time being fit for smoking in a pleasing, satisfactory, and desirable manner, and the object of my invention is to produce the same results by artificially 95 smoking the pipe or treating same in such a way that a "broken in" pipe results initially as an article of manufacture, for thus the purchaser need not "break in" such 100 newly purchased pipe.

In charring the mixture on the walls of the bowl, or in smoking the pipe artificially after the sugar syrup and other ingredients have been applied to the inner surface of the bowl, the tobacco, licorice, and other ingredients and their by-products adhere to the carbon produced by charring the sugar, and the resulting cake may contain carbon, 110 carbonaceous material, refractory oxides, tar, resins, and the like.

What I claim as new and my invention and desire to secure by Letters Patents is:

1. A process for treating smoking pipe bowls, consisting in completely sealing up the draft-hole at the bottom of the bowl and then coating the inner wall of the bowl with materials different than the material of which the bowl is composed and including tobacco or derivatives of tobacco, and then applying heat inside the bowl until the applied materials have been chemically changed and fixed to the wall of the bowl as a not readily removable cake containing derivatives of tobacco and other materials.

2. A process for treating smoking pipe 120

bowls, consisting in first sealing up the draft-hole at the bottom of the bowl, applying to the inner surface of the bowl a viscous mixture of sugar, tobacco, licorice, and water, and then applying heat inside the bowl until the applied materials have been chemically changed and fixed to the wall of the bowl as an adhering cake containing carbon, tars, resins, nicotine, ash, 10 refractory oxides, and other materials.

3. A process for treating smoking pipe bowls, consisting in first sealing up the draft-hole at the bottom of the bowl, ap-

plying to the inner surface of the bowl a viscous mixture of sugar, tobacco, licorice 15 and water, and then applying heat and a forced circulation of air inside the bowl until the applied materials have been chemically changed and fixed to the wall of the bowl as an adhering cake containing carbon, tars, resins, nicotine, ash, refractory 20 oxides, and other materials.

In testimony whereof, I affix my signature at Cincinnati, Ohio, this 3rd day of April, 1922.

HAROLD F. RICHARDS.
